To all whom it may concern:

Be it known that I, Jack B. Stuman, a citizen of the United States, residing at Rockford, in the county of Winnebago and State of Illinois, have invented a new, original, and ornamental Design for a Back Panel Unit for Gas Stoves or Ranges, of which the following is a specification, reference being had to the accompanying drawings, forming part thereof.

In the drawing:

Figure 1 is a top plan view of a back panel unit for gas stoves or ranges embodying my new design;

Figure 2 is a front elevational view thereof;

Figure 3 is an end elevation thereof, taken from the left end of the back panel unit; and

Figure 4 is an end elevation thereof, taken from the right end of the back panel unit.

I claim:

The ornamental design for a back panel unit for gas stoves or ranges, substantially as shown.
